Inventor:
John Fish.

UNITED STATES PATENT OFFICE.

JOHN FISH, OF NEW YORK, N. Y.

IMPROVEMENT IN STEAM-ENGINES.

Specification forming part of Letters Patent No. 10,615, dated November 17, 1863.

To all whom it may concern:

Be it known that I, JOHN FISH, of New York, in the county of New York and State of New York, have invented a new and useful Improvement in Steam-Engines; and I do hereby declare that the following is a full and exact description thereof, reference being had to the accompanying drawings, making a part of this specification, and to the letters of reference marked thereon, in which—

Figure 1 is a longitudinal elevation. Fig. 2 is an end elevation; Fig. 3, a plan. Fig. 4 is a detailed drawing of clutch L. Fig. 5 is a detailed drawing of balance clutch-wheel H. Fig. 6 is a detailed drawing of cross-head E.

The nature of my invention consists, first, in a single-cylinder engine, having two pistons, with their rods, each working through the opposite cylinder heads, the arrangement and construction of a cross-head in connection with the piston-rod of one piston, so as to allow the piston-rod, cross-head, and connecting-rod of the other piston to work through it, by which means two connecting-rods of equal length can be obtained, each working upon opposite cranks upon the same shaft; second, in a single cylinder engine, the arrangement of a vacuum or pumping engine in such a manner that the balance-wheel of the vacuum or pumping engine is hung or runs upon the shaft of the main engine, so that by moving a clutch upon the shaft of the main engine into gear with the balance clutch-wheel of the vacuum or pumping engine, both engines can be connected at right angles or they can be worked independent of each other.

To enable those skilled in the art to make and use my invention, I will proceed to describe its construction and operation.

I construct my engine with one steam-cylinder, (marked A in Figs. 1 and 3,) with two pistons, B b. The steam-cylinder has one central induction-port to admit steam between the two pistons, causing them both to recede. Steam is admitted for the return-stroke through a port at each end of the cylinder, the steam in this case acting between the cylinder-heads and the pistons, with their piston-rods each working through its own cylinder head—namely, C through D, and c' through d'. The piston-rod e, I connect to the cross-head E by means of the cross-tail o and side rods, P P.

In the cross-head E there is a space or aperture to allow the piston-rod c', cross-head e', and connecting-rod f' to work through upon its own crank, g'. There is also a journal-wrist upon cross-head E in line with the crank-pin of crank G. The journal on cross-head E and crank G are connected by means of the connecting-rod F, which is equal in length to the connecting-rod f' of the piston-connection b' c' e' f' g'.

I am aware that two pistons in one cylinder, each working through the opposite cylinder-head, is not new. I am also aware that two pistons, with their rods and connections, each working upon opposite cranks upon the same shaft, have been used by Bodmer, of Manchester, England; but in the latter case the connecting-rods were of an unequal length, thereby throwing and causing an unequal strain upon the cranks.

My improvement consists in obtaining in the above-described engine two connecting-rods of equal length by means of the cross-head, as above described.

Single-cylinder engines having one crank or two cranks, one of them opposite the other, are liable to stop upon the center. I arrange my vacuum or pumping engine I J (see Figs. 1, 2, 3) in such a manner that its balance clutch-wheel H is hung or runs upon the main engine-shaft K, so that by sliding the clutch L along the shaft (which it is free to do, but can only revolve with the shaft) into gear with the balance clutch-wheel H the two engines can be connected at right angles to each other, by which means the vacuum or pumping engine can be used to turn the main engine off the center, or they can be worked independent of each other.

I am aware that double engines have been arranged by means of a clutch or other similar device to work together or independent of each other. This is not new. My improvement consists in arranging the balance-wheel of my vacuum or pumping engine in such a manner that the power of this engine can be used to turn the main engine off the center. Therefore,

What I claim as my invention, and desire to secure by Letters Patent, is—

In a single-cylinder engine, having two pistons, with their piston-rods, each working

through the opposite cylinder-heads, the arrangement of the cross-head E, in connection with the piston-rod of piston B, whereby the piston-rod, cross-head, and connecting-rod of piston b' can work through the space or aperture of cross-head E upon their own crank, by which means two connecting-rods of equal length can be obtained, each working upon

an opposite crank upon the same shaft, substantially as specified, and in the manner herein set forth.

JOHN FISH.
